UNITED STATES PATENT OFFICE.

FRED PETERSON, OF AMSTERDAM, NEW YORK.

DESIGN FOR A COMBINATION-BRACKET.

48,665.

Specification for Design.

Patented Feb. 29, 1916.

Application filed November 20, 1915. Serial No. 62,654. Term of patent 7 years.

To all whom it may concern:

Be it known that I, FRED PETERSON, a citizen of the United States, residing at Amsterdam, in the county of Montgomery and State of New York, have invented a new, original, and ornamental Design for Combination-Brackets, of which the following is a specification, reference being had to the accompanying drawing, forming a part thereof.

In the drawings: Figure 1 is a perspec-

tive view; and Fig. 2 is a rear elevation of a combination bracket, showing my new design.

I claim:

The ornamental design for a combination bracket, as shown.

FRED PETERSON.
